(57) CLAIM

The ornamental design for a headboard and footboard set, as shown and described.

DESCRIPTION

FIG. 1 is a left front perspective view of a headboard and footboard set showing my new design;

FIG. 2 is a side elevational view of a headboard and footboard set, the opposite side being a mirror image thereof;

FIG. 3 is a front elevational view of the headboard section thereof;

FIG. 4 is a front elevational view of the footboard section thereof;

FIG. 5 is a left rear perspective view of the footboard section thereof; and,

FIG. 6 is a top view of the footboard section thereof.

The rear and top views of the headboard section and the bottom views of the headboard and footboard are not shown and form no part of the claimed design. The dashed lines represent environmental elements only and form no part of the claimed design.
